UNITED STATES PATENT OFFICE

2,324,837

ELECTRIC HEATER

Chester I. Hall, Rexford, N. Y., assignor to General Electric Company, a corporation of New York

Application August 29, 1942, Serial No. 456,660

7 Claims. (Cl. 219—40)

This invention relates to electric heaters, more particularly to electric heaters of the electrode type which function to heat a substance by passing current through it, and it has for its object the provision of an improved electric heater of this character.

This invention is particularly applicable to an electric heater of the electrode type for heating liquids, such as milk, vegetable and fruit juices, beer and the like in order to pasteurize the liquid. In order to pasteurize liquids of this character, it is extremely important that every part of the liquid be heated to the critical pasteurizing temperature and that this temperature be held for a predetermined period of time. If this is not done, particles of the liquid may retain a colony or colonies of bacteria which later will grow and contaminate the whole.

In certain commercial pasteurizers now on the market, the liquid is forced to flow upwardly continuously through an electrode chamber, the walls of which are defined in part by spaced electrodes. As the liquid passes through the chamber it is heated to a predetermined temperature by the passage of alternating current through it from one electrode to the other. Generally, these electrode chambers have had a pair of opposed electrodes which subjected the liquid stream of a uniform current density, and consequently heated all particles of the liquid uniformly to insure complete pasteurization.

These electrode chambers inherently impose a single phase load on the power system. This was not objectionable as long as the capacity of the apparatus was relatively small; thus, a milk pasteurizer, which handled about 150 gallons per hour, has an electrical rating of about 18 kilowatts, which is not great enough to impose too unfavorable conditions on the generating equipment. However, it has been proposed to increase the capacity of certain milk pasteurizing apparatus to about 1000 to 1200 gallons per hour. Such an apparatus requires an electrical supply of more than 100 kilowatts.

Such a large single phase heater when connected to a three-phase power system imposes a serious unbalanced load upon the transmitting and generating equipment, which as is well known is attendant with undesirable operating conditions in the equipment.

This invention contemplates the provision of an improved pasteurizer electrode chamber which will obviate this objectionable feature of the single phase double electrode chamber.

In accordance with this invention, the elec-

trode chamber is provided with three electrodes which are adapted to be connected to the three supply wires of a three-phase power source; the load imposed on the electrode supply system therefore is balanced.

It further contemplates the provision of such a chamber which will give uniform current density throughout the liquid stream, thus insuring uniform heating of all particles of the liquid. This is accomplished by giving the electrode surfaces in contact with the liquid a predetermined convex curvature with relation to the spacing between them.

In addition, another object of this invention is the provision of an improved cooling system for preventing overheating of the electrode surfaces that contact the liquid stream. In one form of this invention, this system includes cooling liquid passageways directed through the interior of the electrodes themselves.

Other objects of this invention include the provision of an electrode chamber structure which lends itself to easy assembly and disassembly, and which is inexpensive in construction.

For a more complete understanding of this invention, reference should be had to the accompanying drawing in which Fig. 1 is a vertical sectional view of a three-phase electrode pasteurizing chamber embodying this invention; Fig. 2 is a sectional view taken through the line 2—2 of Fig. 1 and looking in the direction of the arrows; Fig. 3 is a sectional view taken through the line 3—3 of Fig. 1 and looking in the direction of the arrows; and Fig. 4 is a diagrammatic representation of the electrode chamber of Figs. 1—3 illustrating the manner in which it is connected into the liquid pasteurizing circuit, and also the way in which it is connected to a three-phase electrical power source.

Referring to the drawing, this invention has been shown in one form as applied to a three-phase electrode chamber for pasteurizing milk. This chamber, as shown, comprises a pair of opposed end members—an upper member 10 and a lower member 11. These members are formed of any suitable mechanically strong, electrically insulating material, such as porcelain.

Mounted in the space between the end members 10 and 11 is an electrode chamber 12. This is defined by the end members 10 and 11, by three electrodes 13, spaced 120° apart, and by three electrically insulating walls 14 inserted between the electrodes. The electrodes 13, as shown, are substantially homogeneous, and are formed of

any suitable material—preferably carbon; and while the walls 13 may be made of any suitable non-conducting material, I prefer to form them of glass. Suitable gaskets 14 are interposed between the electrodes 12 and the walls 13 in order to make fluid-tight joints between these members. It will be observed that the electrodes 12 and glass walls 13 extend throughout the full distance between the two end members 10 and 11, which members preferably will be provided with recesses 15 and 16 respectively in their opposed surfaces to receive the end sections of the electrodes and walls. Inserted in these recesses between the end surfaces of the electrodes 12 and walls 13, and the bottom walls of the recesses are sealing gaskets 15a and 16a.

As shown, the outside surfaces 16b of the electrodes 12 have an arcuate shape. Encircling these surfaces so as to secure the electrodes 12 and walls 13 together are upper and lower clamping rings 17 and 18. Each of these members is in the form of a broken ring provided with outwardly extending flanges 19 at the ends. These flanges are clamped together by means of bolts 20.

The clamping rings 17 and 18 also function to clamp suitable electrical supply contact members 21 to the outer surfaces 16b of the electrodes. These members have about the same length as the electrodes and extend from one edge thereof to the other, and have flanges 21a formed on their lower ends with which to make electrical connections with a source of electrical supply. Interposed between the end edges of the contacts 21 are arcuate-shaped insulating sheets 22, which will be made of any suitable material, such as Textolite. Preferably and as shown, suitable shims 23 will be inserted between the tops and bottoms of the glass insulating walls 13, and the insulating sheets 22. These also will be made of an electrically insulating material, such as Textolite.

Surrounding the contacts 21 and the insulating sheets 22 is a cylinder 24 formed of a suitable electrically insulating material, such as Textolite. This cylinder also is secured by the rings 17 and 18, as shown.

The outer insulating cylinder 24 is provided with three windows 25 opposite the glass insulating walls 13 so that the milk stream may be viewed.

The two end sections 10 and 11 are clamped together by means of a plurality of elongated bolts 27 which, as shown, are directed through upper and lower metallic end plates 28 and 29 fitted to the top and bottom surfaces of the end members 10 and 11 so as to clamp them together. Interposed between these surfaces of the end members and the plates 28 and 29 are suitable sealing gaskets 30 and 31 respectively.

The end member 11 has a fluid supply passageway 32 connected with the electrode chamber 11a while the end member 10 is provided with a fluid discharge passageway 33 connected with this chamber. It will be understood that in the operation of the apparatus, the milk stream to be treated is forced upwardly through the passageway 32 into the electrode chamber 11a and thence is discharged out through the passageway 33 to conduct the milk away from the apparatus; as shown, a suitable milk supply pipe 34 communicates with the passageway 32, while a suitable discharge pipe 35 is connected with the discharge passageway 33. It will be

observed, therefore, that the electrodes 12 and insulating walls 13 extend upwardly parallel to the direction of flow of the liquid stream.

It is contemplated that the three electrode contact plates 21 will be electrically connected respectively with the three conductors of a three-phase supply system 36, as shown in Fig. 4. In order that the electrodes 12 thus supplied will subject the liquid stream flowing opposite them to a uniform current density throughout, I give the electrode surfaces 37 which contact the liquid stream a convex curvature, as shown in Fig. 3; the curvature of the surfaces 37 is such that the current density in the liquid stream in any area normal to the direction of flow is substantially uniform, whereby the liquid flowing through the electrode chamber is uniformly heated. It will be observed that the surfaces 38 of the walls 13 contacting the liquid stream will be given a plane surface normal to the milk flow.

The electrodes 12 must be cooled in order to prevent them from attaining too high a temperature which might result in burning particles of the liquid. The cooling system arranged in accordance with this invention includes passageways 39 which are formed in the electrodes themselves. In other words, the electrodes are hollow and are so arranged that a relatively large liquid passageway is formed through them. Cooling water is forced through the electrodes in a direction opposite to the direction of flow of the fluid in the electrode chamber 11a. The cooling water is forced continuously into the upper ends of the electrodes, is caused to flow down through them, and then is discharged from the electrodes at the bottom. In order to supply the electrodes with the cooling water the upper end member 10 is provided with a circular passageway 40 into which the water is fed by means of a supply pipe 41. The circular passageway 40 is connected with the three electrode chambers 39 by three vertical passageways 42. The lower end member 11 is provided with a similar circular passageway 43 connected with the lower ends of the channels 39 by means of three passageways 44. Connected with the discharge passageway 43 is a discharge pipe 45 which has a pinched section 46 that functions to keep full columns of the cooling water in the hollow electrodes.

As pointed out previously, the three electrodes are connected to the three conductors respectively of a three-phase alternating current supply source 36. The voltage of this source is controlled by means of a temperature-responsive element 49 which responds to the temperature of the milk stream flowing away from the electrode chamber so that a substantially constant temperature is held in the milk stream. While any suitable temperature responsive element may be used, I prefer to use an element of the type described and claimed in my Patent No. 2,271,975, dated February 3, 1942. As there described, this element is such that its electrical resistance varies widely with temperature changes. Any suitable controller 50 which will operate responsively to such changes in resistance may be used to control the voltage applied to the electrodes in order to hold the temperature constant.

It will be observed that one of the features of this invention is the provision of means for readily disassembling the electrode chamber and for reassembling it. To disassemble the chamber, it is merely necessary to remove the large bolts 27 which releases the end members 10 and 11 from the electrodes 12 and their insulating walls 13.

These walls may be separated merely by removing the bolts 20 of the clamping rings. To reassemble, it is of course only necessary to place the walls 12 and 13 together, along with the supply contacts 21, insulating members 22, and insulating cylinder 24, and then clamp these members together by the two rings 17 and 18.

While I have shown a particular embodiment of my invention, it will be understood, of course, that I do not wish to be limited thereto since many modifications may be made, and I, therefore, contemplate by the appended claims to cover any such modifications as fall within the true spirit and scope of my invention.

What I claim as new and desire to secure by Letters Patent in the United States is:

1. An electric pasteurizing device comprising a pair of electrically insulating end members, a plurality of spaced hollow electrodes extending between said end members, said end members having fluid passageways therein arranged to interconnect said electrodes so that a cooling fluid may be circulated between said end members through the interior of said electrodes, insulating members extending between said electrodes, and said end members, electrodes and insulating members being arranged to define a heating chamber for heating liquid circulated therethrough.

2. Electric pasteurizing apparatus adapted to be energized from a polyphase source of electric power comprising an electric heater having a plurality of spaced electrodes adapted to be connected to the various phases of said source of power, and also having a plurality of spaced electrically insulating members interposed between said electrodes, said electrodes and insulating members defining a chamber in which the liquid to be heated is received, all of the surface areas of said electrodes that contact with the liquid have a predetermined form such that the current density through the liquid is substantially uniform whereby the liquid is substantially uniformly heated.

3. Pasteurizing apparatus comprising an electric heater having an electrode chamber through which liquid to be heated is circulated in a predetermined direction, a plurality of spaced electrodes disposed in said chamber and extending in the direction of flow of liquid through said chamber, said electrodes being hollow so as to define internal passageways extending therethrough, and means for circulating a cooling fluid through said electrodes so that it flows in the direction opposite of the direction of flow of said liquid.

4. An electric heater comprising a pair of opposed end members formed of electrically insulating material, said members having shallow circular recesses in their faces opposing each other, an electrode assembly having a plurality of spaced electrodes having arcuate-shaped exterior surfaces, a plurality of insulating members between said electrodes, readily detachable bands clamping said electrodes and insulating members together, said assembly being interposed between said end members so that its ends are received in said recesses, and readily detachable clamping means securing said end members together.
5. A device for heating liquid by passing an electric current therethrough comprising a pair of end members formed of electrically insulating material, a plurality of spaced electrodes extending between said end members, insulating members extending between said electrodes, said end members, electrodes, and insulating members being arranged to define an electrode chamber for heating liquid contained therein, said electrodes having cooling passageways extending through them and said end members having fluid passageways therein arranged to interconnect said electrodes so that a cooling fluid may be circulated between said end members through the interior of said electrodes.
- 15 6. Electric pasteurizing apparatus adapted to be energized from a source of three-phase electric power comprising an electric heater having a chamber through which liquid to be heated is circulated, said chamber having three equally spaced electrodes and three equally spaced electrically insulating members between said electrodes, said electrodes and insulating members defining the chamber through which the liquid to be heated is circulated, and said electrodes and insulating members extending substantially parallel to the direction of the liquid flow, the surfaces of said insulating members in contact with the liquid being substantially flat, and the surfaces of said electrodes in contact with said liquid having a convex curvature such that the current density through the liquid in any area normal to the direction of flow is substantially uniform whereby liquid flowing through said chamber is substantially uniformly heated.
- 20 7. A milk pasteurizing electrode having substantially homogeneous walls formed of carbon, one of said walls having a surface adapted to be exposed to the milk stream, and said walls defining an internal passageway through the electrode for receiving a cooling fluid.
- 25 30 35 40 45 50 55

CHESTER I. HALL.
